(57) **CLAIM**

The ornamental design for a surgical cutter, as shown and described.

DESCRIPTION

FIG. 1 is a top view of the surgical cutter according to the present invention.

FIG. 2 is a left side view of the surgical cutter of FIG. 1.

FIG. 3 is a front view of the surgical cutter of FIG. 1.

FIG. 4 is a right side view of the surgical cutter of FIG. 1.

FIG. 5 is a rear view of the surgical cutter of FIG. 1; and,

FIG. 6 is a bottom view of the surgical cutter of FIG. 1.
The broken lines represent unclaimed portions of the article
and form no part of the claimed design.

1 Claim, 6 Drawing Sheets

FIG. 1

FIG. 2

FIG. 3

FIG. 4

FIG. 5
